UNITED STATES PATENT OFFICE.

BENJAMIN GALLSWORTHY, OF PORT ARTHUR, TEXAS.

STILL.

1,294,357.

Specification of Letters Patent. Patented Feb. 11, 1919.

Application filed June 8, 1916. Serial No. 102,391.

To all whom it may concern:

Be it known that I, BENJAMIN GALLSWORTHY, a subject of the King of Great Britain, residing at Port Arthur, in the county of Jefferson and State of Texas, have invented certain new and useful Improvements in Stills, of which the following is a specification.

This invention relates to new and useful improvements in a still.

The object of the invention is to provide a still of the character described, especially designed for the purpose of refining crude petroleum, and more particularly for the purpose of extracting the lighter elements therefrom.

A further feature of the invention resides in the provision of a gutter arranged around the inner wall of the still, and of gutters arranged underneath the roof thereof into which the condensed distillate, collecting on the walls and roof, drains.

With the above and other objects in view, the invention has particular relation to certain novel features of construction, arrangement of parts, and use, an example of which is given in this specification and illustrated in the accompanying drawings, wherein:—

80 Figure 1, shows a vertical sectional view of the still, taken on the line 1—1 of Fig. 2.

Fig. 2, shows a horizontal sectional view thereof, taken on the line 2—2 of Fig. 1, and

85 Fig. 3, shows a plan view of the troughs employed in the still.

Referring now more particularly to the drawings wherein like numerals of reference designate similar parts in each of the fig-

ures, the numeral 8 designates a vertical 40 cylindrical tank, having a wall gutter 9 extending entirely around and provided for the purpose of receiving the distillate condensed on the tank walls above the surface 45 of the liquid being treated, and which inclines toward the outlet pipe 6. This tank has the roof 10, which is preferably corrugated and spaced underneath it are the respective corrugations of the trough 11, which unite in a chute 11', which discharges 50 the fluid through the outlet 12, into a suitable receiving tank, (not shown). The trough 11 and the chute 11' are supported in the tank by any suitable means, preferably by means of inwardly projecting 55 flanges, which are secured to the tank walls and upon which said trough and chute rest. The roof 10 of the tank is provided with a dome 2', and leading from this dome is the vapor line 3', provided to carry away the 60 condensed vapor.

What I claim is:—

A still of the character described, including a tank, a corrugated roof therefor, fixed troughs arranged under the respective corrugations of the roof, said troughs uniting in a common chute, an outlet receiving fluid from the chute, an annular gutter fixed to the still wall underneath said troughs, and an outlet leading from the gutter.

In testimony whereof I have signed my name to this specification in the presence of two subscribing witnesses.

BENJAMIN GALLSWORTHY.
